UNITED STATES PATENT OFFICE.

CARL G. OLSON, OF CHICAGO, ILLINOIS, ASSIGNOR TO ILLINOIS TOOL WORKS, OF CHICAGO, ILLINOIS, A CORPORATION OF ILLINOIS.

LATHE.

1,238,934.

Specification of Letters Patent. Patented Sept. 4, 1917.

Application filed December 1, 1916. Serial No. 134,244.

To all whom it may concern:

Be it known that I, CARL G. OLSON, a citizen of the United States, residing at Chicago, in the county of Cook and State 5 of Illinois, have invented a certain new and useful Improvement in Lathes, of which the following is a specification.

My invention relates to lathes and is here shown embodied in a lathe in which the work is rotated and the tool has an automatic movement both parallel to the axis of rotation of the work and crosswise thereto. The principal objects of my invention are to provide a lathe capable of turning out 15 very accurate work and having great durability combined with lightness in weight and a minimum number of parts. Other objects of the invention are to provide advantageous means for imparting longitudinal movement 20 to the carriage, for imparting cross-motion to the tool and to provide other mechanical expedients, the principles of which will be explained.

I accomplish my objects by the mechanism 25 illustrated in the accompanying drawings, in which:

Figure 1 is a front elevation of the complete machine, certain minor parts being shown in section.

Fig. 2 is an elevation of the machine, chiefly in section, on the line 2—2, Fig. 3.

Fig. 3 is a plan section on the line 3—3, Fig. 1.

Fig. 4 is a cross sectional elevation on the line 4—4, Fig. 3.

Fig. 5 is a cross sectional elevation on the line 5—5, Fig. 3.

Fig. 6 is an end view looking toward the left in Fig. 1.

Similar numerals refer to similar parts throughout the several views.

In the form selected to illustrate the invention, the frame 1 has longitudinal ways 2 which support the longitudinally traveling carriage. The carriage is preferably saddle shaped having a top 3 and depending aprons 4 which pass down over the outside of the ways. The carriage is of great length, extending in the present case for a distance 50 equal to the combined length of the lead screw, main spindle and cross carriage. This length covers a considerable portion of the entire length of the machine and results in two or three important characteristics.

In the first place, the guiding surfaces are

so long that the travel of the carriage is very true. There is practically no lost motion and in consequence, the tool is held accurately at the proper point and produces accurate work. Another result is that a great bearing surface is afforded, thus distributing the pressure (due to the stresses set up by the action of the tool) over a large area, with a proportionate reduction in wear. This makes for durability in the machine. Another result is that the carriage with its surmounted parts is relatively heavy and is therefore not subject to vibration.

In the present form of invention, the travel of the carriage is produced by special mechanism which I shall now describe commencing with the part where the driving power is applied to the machine: The main drive shaft 10 is driven by a pulley 11 and belt 12 or other suitable source of power. Rigidly fastened to said shaft is a gear wheel 13 which meshes with a gear wheel 14 as clearly shown in Figs. 2 and 4. Wheel 14 is rigidly secured to the worm shaft 15 which is provided with a worm 16 which drives the worm gear 17. This worm gear is keyed to the main spindle 18 and is held against longitudinal motion, by a collar 19 at one end of the hub and a threaded ring 20 at the other. A housing 22 is provided with suitable bearings both for the shaft 15 and for the spindle 18. These bearings may assume various forms and need not be described in detail.

Spindle 18 has a chuck 31 for holding the work. It also has a tapered socket 23 at the rear end which receives the correspondingly tapered end 24 of the lead screw 25. In the form shown, these parts screw together and are held by a lock nut 26. By preference, the mating surfaces of the interfitting parts is five or six times their diameter. This gives good alignment and rigidity of connection. The outer end of the lead screw works in a suitably threaded nut 28 mounted upon the stand 29 fastened to the rear end of the carriage, as clearly shown in Figs. 1, 2 and 3. It will be noted that in this construction the axis of the lead screw is coincident with the axis of the main spindle 18 of the machine; also, that the lead screw is directly over the carriage and occupies a position intermediate of the outer edges of the ways which guide the carriage. The result is that bending moments and torsional

stresses as well as lost motion are almost entirely eliminated. This, taken in connection with the great length of the carriage, produces a most accurate and efficient mechanism for producing and controlling the movements of the carriage. The forward end of the spindle 18 has, in the preferred form, a collar 32 of large diameter which bears against the bushing 33, supported in the housing 22, as best shown in Fig. 2. Said bushing is externally threaded at each end for taking nuts 34 and 35. This forms an adjustable thrust bearing of ample proportions.

15 The machine is provided with a tail stock 38 which may assume any suitable form. In the present instance, it rests upon the guide ways 2 and is clamped in position by means of a clip 39 held by a bolt 40, as shown in detail in Fig. 6.

20 From the foregoing it will be evident that when the drive shaft 10 is rotated, the lead screw 25 will rotate and will advance the carriage 3. I will now describe the cross carriage and the means by which it is operated:

25 The tool, which is typified by the part 45, shown in Figs. 3 and 5, is fastened in the tool carrier 46, mounted upon slide 47. Slide 47 is mounted upon the cross-carriage 48 and has ways 49 for guiding the tool slide crosswise of the machine. Slide 47 is adjusted by means of a hand wheel 50, a shaft 51 and screw mechanism of any suitable type. Such 30 screw mechanism is too well known to require detailed description. Cross carriage 48 is guided crosswise of the machine by ways 53 formed upon the tool table 54 mounted on the main carriage 3, as best 35 shown in Figs. 1 and 2. Table 54 is slideable longitudinally of the main carriage by means of a hand wheel 56 operating a train of gears 57 meshing with the stationary rack 58. These parts are shown in detail in Fig.

40 45. A helical compression spring 60 bears at the inner end against a shoulder 61 formed on the main carriage. The other end of said spring abuts a lug 62 slidably mounted upon the cross-carriage 48. Said 45 lug may be adjusted by means of an adjusting screw 63 journaled in a lug 64 rigidly fastened to the cross-carriage. By rotating the screw 63, the compression of the spring may be regulated. The spring constantly urges the cross-carriage toward the front of the machine—that is, toward the operator. Movement of the cross-carriage in the opposite direction—toward the back of the machine—is accomplished by means of a cam 50 67 fastened to a cam shaft 68 and engaging an anti-friction disk or similar element 69 mounted in the back end of the cross-carriage, as shown in full lines in Fig. 5 and in dotted lines in Fig. 3. As the cam shaft is 55 rotated (in an anti-clockwise direction—Fig.

5), the cam wipes the disk and forces the cross-carriage backward against the pressure of spring 60. Thus the cam mechanism, coöperating with said frame, imparts a movement to the cross-carriage crosswise of the machine, and the particular character and timing of the movement depends upon the design of the cam. According to the illustrated design, the cam is in the form of a snail cam, by which the cross-carriage 75 is forced back (toward the work) slowly until the point of the cam is reached, whereupon the carriage is suddenly released and immediately returned by the spring.

70 Cam shaft 68 has two rigid collars 71 80 bearing against opposite cheeks of the cross-carriage and hence causing the shaft to travel lengthwise of the machine in unison with the travel of the cross-carriage. The cam shaft is journaled in suitable stationary 85 bearings 72, 72 and is rotated by means of a bevel gear 73 splined upon it, as best shown in Fig. 3. Said bevel gear is held against lengthwise movement by means of a lug 74 which projects into a groove 75 90 formed in the hub of the bevel gear. From this it will be understood that when said bevel gear is rotated, it will rotate cam shaft 68 in spite of the fact that the shaft is traveling longitudinally in unison with 95 the longitudinal movement of the cross carriage. The longitudinal movement of the cam shaft enables the cam 67 to remain at all times in coöperative relation with the anti-friction disk 69.

100 Bevel gear 73 is rotated by companion bevel gear 78 fastened to a counter shaft 79 driven by a gear wheel 80, as best shown in Figs. 3 and 4. This in turn is driven by gear wheel 81, rigidly fastened to a pinion 83, which drives a spur gear 84 rigidly fastened to worm shaft 15. Shafts 79 and 82 are suitably journaled in a housing 22.

110 In operation, when the power is turned on and shaft 15 is made to rotate, the lead screw 25 will advance the carriage 3 and carry the tool carrier 46 with it, lengthwise of the machine. At the same time, the rotation of the cam shaft 68 produces a comparatively rapid movement of the cross-carriage 48 in a direction crosswise of the machine. This causes the tool to travel toward and from the work held in the chuck 31 of the rotating sleeve or hollow spindle 18. Rotary motion is also, at the same time, imparted to said chuck and spindle, which constantly presents a new surface to the action of the tool. Thus, there are three kinds of motions simultaneously imparted to 115 different parts of the machine, to-wit: the rotation of the main spindle, the longitudinal travel of the main carriage and the cross travel of the cross-carriage which is 120 mounted upon and travels with the main 125 carriage.

carriage. As a result of these three kinds of motion, I am able to automatically produce shapes of a configuration which would otherwise be difficult, if not impossible, to 5 produce automatically and am able to produce and reproduce them with speed, accuracy and uniformity.

As a specific characteristic, it will be noted that the power is applied to the main 10 spindle 18 at a point between the two bearings which support it. This decreases the strain to which the spindle is subjected in receiving its driving power. I would also call attention to the fact that the long bearing surface of the main carriage 3 is of great 15 advantage in distributing the downward pressure which is exerted by the action of the rotating work upon the tool. By reference to Fig. 5, it will be evident that the 20 work rotates in an anti-clockwise direction and that the tool engages the front or downwardly moving part of the work. In consequence, there is a downward pressure on the cross-carriage and a downward pressure 25 on the main carriage. The ways or guide surfaces of the main carriage are, however, so large that this downward pressure is of negligible effect.

Attention is called to my co-pending application for lathes filed December 1, 1916, 30 Serial No. 134,245.

Having thus described my invention, what I claim as new and desire to secure by Letters Patent is,:

35 1. A lathe having a main frame, a carriage sliding upon it, a lead screw for causing the carriage to travel, a main spindle for rotating the work, the lead screw and spindle having a common axis and being 40 rigidly connected together, and a tool carrier located on said carriage at the end of the spindle opposite to the lead screw, the carriage having a bearing surface upon the main frame beneath the axis of the lead 45 screw.

50 2. A lathe having a main frame, a carriage sliding upon it, a lead screw for causing the carriage to travel, a main spindle for rotating the work, the lead screw and spindle being fastened together end to end, and a tool carrier mounted on said carriage, the carriage having a bearing surface upon the main frame of a length substantially as great as the combined length of the lead 55 screw and spindle and longitudinal dimension of the tool carrier.

3. A lathe having a main frame, a main carriage slidably mounted upon said frame, said carriage having a tool carrier at one end 60 and a lead nut at the other, a main spindle for rotating the work, a lead screw in line with the spindle and fastened thereto, the carriage being continuous from the tool carrier to the lead nut, and a stationary bearing between the tool carrier and the lead nut

for supporting the main spindle, said bearing being supported from the side of the carriage, and the carriage passing beneath the bearing.

4. A lathe having a main frame provided with ways arranged longitudinally, a carriage traveling upon said ways, a tool carrier mounted at one end of said carriage, a standard at the other end of said carriage, a nut carried by said standard, a lead screw 70 working in said nut, and a main spindle fastened to the end of said screw and extending toward the tool carrier, said spindle and lead screw rotating in unison about coincident axes, the carriage having a bearing surface upon the ways of the main frame extending from the outer end of the tool carrier to the outer end of the standard.

5. A lathe having a main frame, a main carriage traveling longitudinally thereon, a work spindle rotatably mounted upon said main frame, a cross carriage for supporting the tool, said cross carriage being mounted upon the main carriage and traveling in a crosswise direction independently of the main carriage, and actuating means common 90 to said spindle and to said cross carriage for rotating said spindle and moving the cross carriage transversely to the axis of the spindle.

6. A lathe having a stationary frame with a main carriage traveling longitudinally on it, a spindle for rotating the work, a lead screw for causing the carriage to travel, said lead screw rotating in unison with the spindle and being in line therewith, a cross carriage located at the operative end of the main spindle, cam mechanism for producing cross movement of the cross carriage, and a power device common to the main spindle 100 and to the cam mechanism for rotating the main spindle and lead screw and operating the cam mechanism.

7. A lathe having a stationary frame, a main carriage traveling on it, a main spindle, a lead screw for causing the carriage to travel, the lead screw and spindle being fastened together end to end, and being non-shiftable in an axial direction, a cross carriage for carrying the tool, said cross carriage being located on the main carriage at the outer end of the main spindle, a spring for moving said cross carriage in one direction, a cam for moving said carriage in opposition to said spring, and means common 115 to said main spindle and to said cam for rotating them.

8. In combination, a stationary frame, a main carriage traveling on it, a lead screw for causing the carriage to travel, a main 125 spindle fastened to the lead screw end to end, a cross carriage for carrying the tool, said cross carriage being located on the main frame adjacent to the outer end of the main spindle, a spring for moving said cross car- 130

riage in one direction, a cam for moving it in opposition to said spring, means common to said main spindle and to said shaft for rotating them and means for adjusting the exten-

5 tent to which the spring is strained.

9. A lathe having a main spindle for rotating the work, a main carriage traveling parallel to the axis of the spindle, a lead screw fastened to said main spindle in line therewith, a cross carriage carrying the tool and movable crosswise of the main carriage, a coöperating cam and spring acting upon the cross carriage for operating it, and means for rotating the cam in proportion to

10 the speed of the spindle.

10. A lathe having a main spindle for rotating the work, a main carriage traveling parallel to the axis of the work, a lead screw fastened to said main spindle in line therewith, a cross carriage carrying the tool and slidably mounted on the main carriage so as to slide thereon transversely to the axis of the main spindle, a coöperating cam and spring and means for rotating the cam at a

definite speed for thereby operating the 25 cross carriage in timed relation with the travel of the main carriage.

11. A lathe having a main frame, a non-traveling rotating main spindle, and a main carriage extending beyond both ends of the 30 spindle, said carriage supporting the tool carrier at one end of the spindle and at the other end of the spindle having a feed connection with the carriage.

12. A lathe having a main frame, a non-traveling rotating main spindle, a non-traveling tail stock opposite to the forward end of the main spindle, a main carriage projecting at both ends beyond the main spindle and having a tool carrier at one end of the 40 main spindle and a threaded nut at the other end, and a lead screw fastened to the main spindle in line therewith and passing through said nut to thereby cause the carriage to travel.

45 In witness whereof, I have hereunto subscribed my name.

CARL G. OLSON.
